FREDERICK GANSERT AND HERMAN GANSERT, JR., OF SYRACUSE, NEW YORK.

METHOD OF FORMING AND ALINING TYPE ON THE TYPE-BARS OF TYPEWRITING-MACHINES.

1,380,709.

Specification of Letters Patent. Patented June 7, 1921.

Application filed October 27, 1920. Serial No. 420,046.

To all whom it may concern:

Be it known that we, FREDERICK GANSERT and HERMAN GANSERT, Jr., both of Syracuse, in the county of Onondaga, in the 5 State of New York, have invented new and useful Improvements in Methods of Forming and Alining Type on the Type-Bars of Typewriting-Machines, of which the following, taken in connection with the accompanying drawings, is a full, clear, and exact 10 description.

This invention relates to a method of forming and alining type on the type bars of typewriting machines having pivoted 15 type bars which are usually assembled in close, compact relation in such manner as to cause their type to assume substantially the same printing position when the bars are operated.

20 In many machines of this character, each type bar carries two or more type or printing characters, which necessitates a very careful adjustment, commonly known as "alining" of the type, in order that both characters 25 may print squarely upon the work in either position of adjustment of the platen or segment and at substantially the same printing point, all of which requires the employment of highly skilled and expensive labor and, 30 therefore, adds materially to the cost of the machine.

In many instances the type are attached 35 to the type bars by means of solder or some equivalent attaching means which will enable the type to be more easily adjusted or alined, after the bars have been permanently assembled in the machine, resulting in more or less unreliability of securement and consequent displacement of the type, after a 40 short period of use.

The main object of my present invention is to avoid the laborious and expensive operations of adjusting or alining the type, after the type bars have been assembled in 45 the machine and at the same time to produce a stronger and more dependable connection between the type and their respective bars, by casting the type directly upon the bars while the latter are assembled in the supporting segment and before they are installed in the machine, and in such manner that when the segment with the bars therein are assembled in the machine, the type will assume the required position for printing 50 at substantially the same printing point

and squarely upon the work in either position of adjustment of the platen or segment.

Another object is to provide means whereby an entire set of type for the machine may be simultaneously cast upon their respective 60 bars in position for proper alinement, when the bars are assembled in the machine without any further adjustment.

Other objects and uses will be brought out in the following description.

In the drawings, Figure 1 is a top plan, partly in section and somewhat diagrammatic, of an apparatus by which the type may be simultaneously cast upon a plurality of bars forming a part of the complete set 70 for a typewriting machine, although, for purposes of illustration, those shown may be regarded as a complete set.

Fig. 2 is a side elevation, partly in section, of the apparatus shown in Fig. 1.

Fig. 3 is an enlarged transverse sectional view of a portion of the same apparatus, taken in the plane of line A—A, Fig. 2.

As illustrated, the apparatus for casting the type, as —1—, upon the type bars, as 80 —2—, comprises lower and upper mold sections —3— and —4—, meeting in the plane of line B—B—, Fig. —2— and adapted to be clamped together and released by suitable bolts —5—.

In many of the machines now in common use, the type bars are pivoted near one end in the arc of a circle, having its axis passing approximately through the printing point, so that when operated from their normal 90 positions of rest they will produce the desired impression upon the work at that point, the type being mounted upon the opposite ends of the bars to swing to and from the normal position of rest, which may also be in the arc of a circle, preferably concentric with the arc in which the pivots are located and a distance therefrom corresponding approximately to the length of the bars, or substantially equal to the distance from 100 the printing point, as —x—, to the pivots. This printing point —x— may be on the front face of the platen of a "visible-writing machine" and the apparatus shown for casting the type upon the bars makes use of the 105 segment —6— of the typewriting machine secured by screws or equivalent fastening devices —7— to one of the mold sections, as —3—, said segment being disposed in a substantially horizontal plane about an axis 110

passing vertically through the printing point —*x*— and having a series of slots —8— radial to said axis and in uniformly spaced relation for receiving the adjacent ends of a corresponding number of the type bars —2— to be used in the machine with that particular segment. These type bars are provided with registering pivot holes through which a wire or other fastening device —9— may be passed to lock the bars to the segment during the process of casting the type on the opposite ends thereof.

These bars fit snugly in their respective slots —8— and extend radially therefrom with their type receiving ends securely held in a corresponding number of similar radial slots —10— in a hardened section —11— of one of the molds, as —4—, the end wall of each slot —10— forming an abutment —12— for the adjacent end of the corresponding bar —2— to additionally hold the bar against endwise movement.

The mold section —3— is also provided with a hardened section —11'— directly opposite the section —11— which, together with section —11'—, are provided with communicating recesses —13— and —14— in their meeting faces to form a series of relatively short and also relatively shallow chambers —15—, registering with the adjacent portions of their respective type bars —2— to receive the molten type metal, which is to be cast therein, around and upon the lower edges of said bars.

That is, the type receiving ends of the bars extend through the upper portions of the recesses —14— a short distance from the lower wall of the recess —13—, each chamber —15— extending upwardly at the side of the corresponding bar a short distance above the lower edge thereof and really forms an enlargement of the corresponding slot —10—, which otherwise is of substantially the same width as the adjacent bar —2— to confine the molten metal to the chamber —15—.

Each of these chambers —15— is connected by a passage —16— to a sprue —17— to which the molten metal is delivered under pressure for simultaneously filling all of the chambers —15— and thereby casting the type directly upon the adjacent portions of all the bars —2—.

If desired, the type receiving end of the bar —2— may be provided with one or more relatively small holes —18— through which the molten type metal may flow to establish an integral tie between the portions of the opposite sides of the bar, and also to increase the permanency of connection between the type and bar.

The type receiving end of each bar is pro-

vided with a rearward projection —19—, which is commonly employed in bars of this character to register with a guide slot (not shown) in the machine just below the printing point to hold the type against the lateral vibration when printing.

When the bars are assembled in the mold, the lower edges of these projections —19— are caused to rest upon suitable pins —20— in the section —11'—, and also to close the intervening space at the rear end of the chamber —13— so as to confine the molten metal in said chamber.

The upper edges of the type receiving ends of the bars —2—, when assembled in the mold, are engaged by pins —21—, which are movable in the upper section —4— and are held in operative position by spring fingers —22— to further prevent displacement of the bar, while the type are being cast thereon.

Although we have not attempted to show the exact relation or angle of the chambers —15— relatively to their respective guide slots —8— and —10—, it is, of course, understood that the angles of the type relatively to their respective bars vary according to their position relatively to the printing point, and, therefore, each chamber —15—, and especially the portion —13— thereof, will be made at a corresponding angle or in proper relation to its guide slots —8— and —10— in the mold.

In other words, each type chamber —15— preferably bears the same relation to its corresponding guide slots —8— and —10— that the type bears to the bar when assembled in the machine for actual use, so that, when the bars with the type cast thereon are assembled in the machine upon their respective bearings, no further adjustment of the type will be necessary thereby avoiding the laborious and expensive work of "alining" after the assembly.

What we claim is:

The herein described method of forming and alining type on the type bars of type-writing machines, consisting in supporting the type receiving portions of the several bars in fixed spaced relation within a suitable type-mold and then casting the type on the bar in a position to cause them to be properly alined for printing, when the bars with the type thereon are assembled in the machine.

In witness whereof we have hereunto set our hands this 18th day of October, 1920.

FREDERICK GANSERT.
HERMAN GANSERT, JR.
